UNITED STATES PATENT OFFICE.

WILLIAM MALLINSON, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,791, dated April 16, 1872.

Specification describing a new and original Design for a Carpet, invented by WILLIAM MALLINSON, of Halifax, in the county of York, England.

The accompanying photograph fully represents my new design.

This invention relates to the new design of two rectangular figures that constitute the more important features of a carpet. The larger of these figures has ornamental projec-

tions in the middle of each side. The smaller is cut at the corners. Both have inner fields and are otherwise ornamented, as shown.

I claim as my invention—

The design for a carpet, consisting of the two ornamental figures, as shown.

WILLIAM MALLINSON.
